CLAIM

The ornamental design for a wireless charger, as shown and described.

DESCRIPTION

FIG. 1 is a front, top and right side perspective view of a first embodiment of a wireless charger, showing my new design; FIG. 2 is a rear, top and right side perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a perspective view of a second embodiment of the wireless charger, with a standard charging port.

FIG. 10 is a perspective view of a third embodiment of the wireless charger, with a standard charging port; and,

FIG. 11 is a perspective view of the design in a detached status.

The broken lines depict portions of the wireless charger and form no part of the claimed design.

1 Claim, 11 Drawing Sheets
